US00D901538S

(12) **United States Design Patent** (10) **Patent No.:** **US D901,538 S**
(45) **Date of Patent:** **** Nov. 10, 2020**

(54) **DISPLAY SCREEN OR PORTION THEREOF WITH ICON FOR PRESENTATION OF ANALYTE DATA**

(71) Applicant: **DexCom, Inc.**, San Diego, CA (US)

(72) Inventors: **Esteban Cabrera, Jr.**, San Diego, CA (US); **Katherine Yerre Koehler**, San Diego, CA (US); **Brian C. Smith**, San Marcos, CA (US); **Eric Cohen**, San Diego, CA (US); **Rian Draeger**, San Diego, CA (US); **Paul Kramer**, Austin, TX (US); **Paul Noble-Campbell**, Austin, TX (US); **Eli Reihman**, San Diego, CA (US); **Leif Bowman**, San Diego, CA (US)

(73) Assignee: **DexCom, Inc.**, San Diego, CA (US)

(**) Term: **15 Years**

(21) Appl. No.: **29/687,454**

(22) Filed: **Apr. 12, 2019**

(57) **CLAIM**

The ornamental design for a display screen or portion thereof with icon for presentation of analyte data, as shown and described.

DESCRIPTION

The patent or application file contains at least one drawing executed in color. Copies of this patent or patent application publication with color drawings will be provided by the Office upon request and payment of the necessary fee.

FIG. 1 shows a front view of a first embodiment of a display screen or portion thereof with icon for presentation of analyte data;

FIG. 2 shows a front view of a second embodiment of the display screen or portion thereof with icon for presentation of analyte data;

FIG. 3 shows a front view of a third embodiment of the display screen or portion thereof with icon for presentation of analyte data; and,

FIG. 4 shows a front view of a fourth embodiment of the display screen or portion thereof with icon for presentation of analyte data.

The inner broken-line rectangle illustrates a display screen. The outer broken-line rectangle illustrates an electronic device. The broken lines form no part of the claimed design.
